UNITED STATES PATENT OFFICE.

SAMUEL DESOE, OF WILLOW CITY, NORTH DAKOTA.

HAY-RACK.

SPECIFICATION forming part of Letters Patent No. 625,096, dated May 16, 1899.

Application filed November 8, 1898. Serial No. 695,846. (No model.)

To all whom it may concern:

Be it known that I, SAMUEL DESOE, a citizen of the United States, residing at Willow City, in the county of Bottineau and State of North Dakota, have invented certain new and useful Improvements in Hay-Racks; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention has for its special object to make a hay-rack which will conveniently serve also as a wagon-body, the same being constructed entirely of metal and adapted to receive a plank flooring. The metal may be galvanized or in any suitable manner protected from oxidation and the deteriorating effects of moisture.

In the drawings, Figures 1 and 2 are perspective views of the upper and lower sides of the rack, respectively.

In the drawings, A represents the rack as an entirety, on which is formed a body by means of the side rails a , end rails a' , standards a^2 , and bottom cross-bars a^3 , with the bottom rails a^4 . On the front and rear I arrange the yokes a^5 , of which there are preferably two in front and one in the rear. To these are attached the ends of the pole, which goes longitudinally across the middle of load, by ordinary ropes or chains. I make them in two parts, hinged at the top of frame or

body, so as to be turned down when necessary.

On the bottom of the rack I secure the angle-bars a^6 , on which are formed the bearings a^7 , that rest on the axles between suitable 40 collars.

a^8 is a cross-brace supported on the standards a^9 , and a^{10} longitudinal braces supported on said standards, but secured to a side arm of the angle-bars a^6 at each end, while $a^{11} a^{11}$ 45 are intermediate braces between the angle-bars $a^6 a^6$.

This rack is found in practice to be light, easily handled, and admirably adapted to its two purposes, while it is cheaper in the long 50 run or considering its durability than one made of wood.

Having thus described all that is necessary to a full understanding of my invention, what I claim as new, and desire to protect by Letters 55 Patent, is—

A vehicle-body having the sides, ends and bottom formed of rails with open spaces between them and provided on the under side of bottom with the axle-bearing angle-bars 60 a^6 ; whereby said body will be light, easily lifted on and off the running-gear, adapted to many different purposes and withal inexpensive.

In testimony whereof I affix my signature 65 in presence of two witnesses.

SAMUEL DESOE.
